ROLL HOLDER

Anthony Badami, Philadelphia, Pa.

Application December 19, 1951, Serial No. 17,777

Term of patent 3½ years

(Cl. D44—29)

To all whom it may concern:

Be it known that I, Anthony Badami, a citizen of the United States, residing in Philadelphia, Philadelphia County, Pennsylvania, have invented a new, original, and ornamental Design for a Roll Holder, of which the following is a specification, reference being had to the accompanying drawing, forming a part thereof.

In the drawing:

Figure 1 is a view in perspective of the roll holder showing my new design;

Figure 2 is a side elevational view of the roll holder; and

Figure 3 is a top plan view of the roll holder.

I claim:

The ornamental design for a roll holder, as shown.

ANTHONY BADAMI.
